UNITED STATES PATENT OFFICE.

THOMAS B. TOWLE, OF DAYTON, OHIO.

SPARKING PLUG.

1,214,390.

Specification of Letters Patent. Patented Jan. 30, 1917.

Application filed June 23, 1913. Serial No. 105,118.

To all whom it may concern:

Be it known that I, THOMAS B. TOWLE, a citizen of the United States, residing at Dayton, in the county of Montgomery and State of Ohio, have invented certain new and useful Improvements in Sparking Plugs; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in sparking plugs. Those familiar with the use of sparking plugs are well aware of the trouble experienced therewith owing to the accumulation of carbon on the sparking points. The accumulation of carbon necessarily interferes with formation of sparks and, further, tends to break down the insulation and to thus render the sparking plug in either case to be useless.

The object of the present invention is to provide means used in connection with the sparking plug for preventing the accumulation of carbon or other matter which will have a tendency to interfere with the proper function of the spark plug.

To this end my invention consists of a screen comprising a wire cap which is secured to the end of the plug in close proximity to the sparking points. In this position the portion of the screen immediately adjacent to the sparking points becomes very hot and maintains a high temperature which has the effect of preventing deposits of carbon on the sparking points, formed on the interior of the engine cylinder, as will hereinafter more fully appear from the following description in connection with the accompanying drawing.

In the accompanying drawing, Figure 1 is a vertical elevation of a sparking plug having my improved means for preventing the accumulation of carbon shown in connection therewith; Fig. 2 is an end view of

the sparking end of the plug; Fig. 3 is an enlarged elevation of the sparking end of the plug with a part of the screen or protecting mantle removed to disclose the sparking points.

Referring more particularly to the drawing, 1 designates a well known form of sparking plug which is used on the interior of an explosive end of a cylinder in a well known manner. The sparking plug as well as its position in the explosive cylinder are well known to those familiar with explosive engines, therefore, it has not been deemed necessary to illustrate any portion of the cylinder nor to describe various well known parts of the spark plug. As shown in Fig. 3, the larger end of the plug supports the sparking points 2 and 3 and it is between and around these points trouble, hereinbefore referred to, occurs, namely, the depositing of carbonized residue. In order to accomplish the object and purpose of protecting the sparking points 2 and 3, I provide a mantle 4 which is constructed of a suitable character of fine mesh. Fig. 3 is an enlarged view of the sparking end of the plug and in this view the wire mesh is exaggerated. In Fig. 2 the wire mesh is also shown somewhat larger than the wire gauze of which the mantle is constructed in actual use. In actual use the meshes or wires constituting the gauze are approximately fifty to the inch, thus forming substantial means for excluding carbon from forming or depositing on the sparking points. This gauze so constituted is in the form of a cap secured on the sparking end of the plug in close proximity to the sparking points. The gauze cap may be secured in such position by any suitable means. In the drawings, I have shown the reduced end 6 of the spark plug supporting the gauze cap by a strand or wire 5 which is tightly wrapped around said portion of the spark plug. The cap immediately in front of the sparking points maintains a high temperature and thereby has the effect of preserving the sparking points from the accumulations of any solid

matter such as carbon or the products of combustion and at the same time it does not retard in the least the ignitions.

Having described my invention, I claim:—

- 5 The combination with a sparking plug for gasolene engines, of a heat-accumulating cap constructed of a woven wire mesh which is secured to the end of said sparking plug below and in close proximity to the sparking
- 10 points and entirely inclosing said sparking

points and by means of which a high temperature is maintained at a point adjacent to the sparking points, substantially as and for the purposes specified.

In testimony whereof I affix my signature, 15 in presence of two witnesses.

THOMAS B. TOWLE.

Witnesses:

M. GALLOWAY,
M. SIEBLER.
